APPARATUS FOR MOLDING A LIQUID BAG

Antonio Richards, Providence, R. I.

Application April 14, 1934, Serial No. 720,523

13 Claims. (Cl. 18—35)

My invention relates to improvements in liquid bags and an object of my invention is to provide a liquid bag particularly one of the hot water type or fountain syringe type provided 5 with a solid integral wall, extending vertically for a substantial distance thereof to prevent the bag from expanding and contracting, or otherwise bowing when filled with liquid in use, said wall being preferably integrally molded in the 10 shaping and manufacturing of the liquid bag. By employing this wall molded integrally with the bag, I am enabled to provide a center wall entirely constructed of the material of the side walls and entirely integral therewith, not depending on its strength for the joining of rubber rods in a separate vulcanization which would tend to distort the bag after the bag has been 15 initially formed.

An object of my invention is therefore to make 20 a molded rubber bag provided with a central wall seamless in every respect.

An object of my invention therefore is to provide 25 an integral wall, or fin which will prevent the liquid bag from bowing when filled with liquid or otherwise getting out of shape, and permanently retaining it in use in the desired flat shape.

It is well known that when rubber surfaces 30 touch each other when dry they tend to become stuck to each other and deteriorate. A further feature of my invention is to continually space the side walls of the liquid bag when not in use by means of my improved molded integral wall.

A further object of my invention is to provide 35 a bag which will accomplish the results named in the two preceding paragraphs without in any way affecting the external appearance or shape of the liquid bag.

Further features of my invention relate to the 40 improved process of molding such a bag with the integral center wall heretofore described and a suitable novel type of mold and core for this purpose to provide a slot therein for the purpose of forming the integral wall.

For this purpose I preferably separate the 45 usual liquid bag core used in the molding operation into two portions, namely, a main portion which may be withdrawn as usual through the 50 distended neck of the bag and a supplemental portion complementary to said main portion except for a vertical slit near the center thereof to form the molded integral wall of my improved liquid bag, which may after the main core has been 55 withdrawn be tilted laterally from the formed

integral wall and readily withdrawn through the neck of my improved liquid bag.

Further features of my invention relate to the 5 detailed construction of such a core and the means I preferably employ to rigidly secure the core in position in a suitable liquid bag mold.

These and such other objects of my invention as may hereinafter appear will be best understood from a description of the accompanying 10 drawings, which illustrate my improved mold, its method of use and my improved liquid bag.

In the drawings, Fig. 1 is a plan view of a lower mold with all portions of my improved core secured thereto after the upper mold has been removed, and showing the molded bag and 15 parts of my composite core in section therein.

Fig. 2 is a sectional view taken along the line 2—2 of Fig. 1 showing the upper mold in place.

Fig. 3 is a sectional view taken along the line 3—3 of Fig. 1 through the center portions 20 of the main core cut-out and supplemental core.

Fig. 4 is a sectional view taken along the line 4—4 of Fig. 1 through the upper portions of the cut-out of the main core and the supplemental core.

Fig. 5 is a plan view of my improved mold and molded liquid bag illustrating the first 30 step of removing the core from the bag, namely that of drawing out the main core through the distended neck of the bag vertically upwardly therefrom and leaving the supplemental core in its molded position below the molded seamless wall, and showing the bag in section.

Fig. 6 is a plan view illustrating the steps in 35 the method of removing the supplemental core from the molded bag by first tilting it laterally away from the molded seamless center wall as shown in dotted lines and drawing it outwardly through the neck as shown in full lines, 40 the molded bag and integral center wall thereof being shown in section.

Fig. 7 is a side elevation of my improved 45 molded bag.

Fig. 8 is a vertical sectional view thereof 45 taken along the line 8—8 of Fig. 7.

In the drawings, wherein like characters of 50 reference indicate like parts throughout, 10 generally indicates a molded liquid bag of flat oblong shape having a body portion 12, a constricted neck 14, side walls 18 and end walls 17 and a central vertical wall 16 integrally 55 molded to the opposite adjacent side walls 18 of said bag in a seamless manner. As stated hitherto, this seamless molded wall 16 prevents 55

irregular bowing or shaping when filled with liquid in use and also spaces the side walls 18 when not in use to prevent any direct contact with each other and hence deterioration 5 of the rubber surfaces thereof. While I am aware that others have attempted to solve this general problem, so far as I am aware they have done so by inserting a plasticizable peg or rod in the bag usually after the initial molding and supplementally cementing or semi-vulcanizing it thereto in a manner to form a seam at each end thereof. By employing my improved core and mold shown herein, and splitting the usual core into a main core and a 10 supplemental core in the manner shown herein, I believe I am able to provide for the first 15 time a liquid bag having a molded integral wall integrally spacing the side walls of the liquid bag.

20 While any suitable plasticizable material may be used for forming my improved bag, I preferably cover a suitable core 20, by wrapping rubber strips therearound or laying rubber layers on the top and bottom thereof, place it in 25 a mold and subject it to a sufficiently high temperature to plasticize the material to form the desired article. While any suitable type 30 of plasticizable material may be used in accordance with the usual practice of making liquid bags, I preferably construct my improved bag out of rubber and for this purpose I preferably wind strips of unvulcanized rubber or layer sheets having the usually desired vulcanized materials incorporated therein around 35 the core prior to inserting it in the mold.

As shown in Fig. 5 my improved core preferably includes a main portion 22 and a supplemental portion 24. These portions 22 and 24 are suitably secured together, the desired 40 rubber wrapped around it and then laid in the lower mold 26 (Fig. 1). Of course, if other types of plasticizable materials are used other than rubber, the core may be placed in the mold and the plasticizable material laid around 45 it or on top of and below it in any suitable manner either before or after insertion of the core in the mold.

My entire apparatus includes the lower mold 26 having the hemi-liquid bag concavity 28, restricted neck concavity 30, and a flat concavity 32 extending from above said neck concavity to the end wall 34 of said mold having holes 36 therein.

As stated, I provide core means adapted to 55 receive winds of rubber or other plasticizable material to be vulcanized and/or molded and to lie therewith in a molding position in the concavities 28, 30 and 32 of said lower mold, including a main core portion 22 of desired 60 shape of the interior of the bag including the body 12 and neck 14 thereof and of the thickness of the bag except for the rounded edges, and constricted neck 30 thereof and a flat portion 40 of the thickness of said bag above the 65 neck thereof and adapted to lie in said flat concavity 32 in said lower mold 26 having holes 42 therein aligned with said mold holes 36. Said main core body portion 22 has a cut-out portion 44 extending downwardly from above 70 the center of said liquid bag portion, slightly offset from the vertical central line thereof including a base portion 46, a center portion 48 of less width, said base portion 46 having holes 50 projecting upwardly therefrom in said 75 core and said center portion 48 having vertical

grooves 52 extending laterally inwardly thereof and an upper portion 54 of less width extending laterally on one side of the vertical central line thereof a slight distance as at 56 (Fig. 1) and a substantial distance as at 58 (Fig. 1) on the other side thereof of the vertical central line thereof. Said main core 22 also preferably has a hole 60 extending vertically upwardly from said second offset side 58 of said upper cut-out portion 54 to the top portion of said core, or outer end of the flat portion 40 of said core.

I also provide a supplemental core portion 24 substantially complementary to said cut-out portions 44 having a complementary base 62 having pins 64 projecting vertically upwardly therefrom within said main core holes 50, a center portion 66 having splines 68 projecting laterally thereof within said main core grooves 52 and an upper portion 70 of less width than said 20 cut-out upper portion 44 extending from the second side 58 of said cut-out to a line 72 spaced from a vertical central line of said mold an amount equal to the amount that the first side 25 of said cut-out is spaced from said vertical center to form a liquid bag wall forming slit 76 (see Fig. 1) extending vertically near the center of said composite core to form the vertically central wall 16 of my improved liquid bag. In my improved construction I also provide a rod 30 78 projecting from the upper portion 70 of said supplemental mold through said hole 60 in said main core and having a threaded end 80 projecting from the upper portion thereof and extending beyond the mold end wall and 35 main core flat portion 40. I also provide a nut 82 adapted to be threaded on said threaded rod end 80 to clamp said core portions 22 and 24 together. It is thus obvious that the pins 64 fitting into the holes 50 and the splines 68 40 fitting into the grooves 52 form means to secure said core portions in alignment and said rod 78 extending through said hole 60 in combination with a clamp or nut 82 form means to detachably secure said core portions together 45 in molding position within said mold. To align the flat main core portion 40 within the cut-out 32 in said lower mold I provide the pin means 84 extending from said holes 42 into the aligned holes 36 in said lower mold to securely 50 align said core on said lower mold. I also provide the upper mold 86 having a cooperating hemi-liquid bag body, neck and flat concavities 88, 90 and 92 respectively adapted to overlie 55 said core 20 and covering thereof to mold the exterior of said liquid bag with said lower mold.

In operation, the supplemental core portion 24 is inserted within said main core portion 22 so that the rod 78 thereof will project through the hole 60 therein, the pins 64 fitting into the holes 50 and the splines 68 fitting into the 60 grooves 52 to secure said core portions in alignment and the nut 82 is then threaded on to the threaded end 80 of the rod 78 to securely clamp said core portions together. Then the strips of unvulcanized rubber having the desired vulcanizing materials incorporated therein are wrapped around or laid on each side of the core and the core is then laid in the lower mold 26, with the pins 84 projecting therefrom through the respective holes 36 in the flat portion of the core 40 to hold the core in position on said lower mold.

As stated hitherto, if desired, other types of plasticizable material than rubber may be em- 75

- ployed which may be either wrapped around the core as stated, or poured or laid into the concavities between the mold and core formed by their specific construction. The upper mold 5 86 is then placed over the lower mold as shown in Fig. 2 and the entire device subjected to the desired molding heat or process with the desired hydraulic or other pressure suitably exerted on said mold. After the rubber has been 10 suitably vulcanized or the plasticizable material otherwise suitably plasticized the upper mold 86 is removed, and as shown in Fig. 5 the core 20 surrounded by the formed bag is withdrawn from the lower mold. The nut 82 is then withdrawn 15 from the threaded end 80 of the bolt 78, thus detaching the main core 22 from the supplemental core 24, the neck 14 of the molded or formed bag 10 is then distended in the usual manner and as shown in Fig. 5 the main core 20 20 22 may be withdrawn out of the distended neck thereof leaving the supplemental core 24 in its molding position underneath and laterally abutting the formed integral wall 16. As shown in Fig. 6 to remove the supplemental core, it is 25 first laterally tilted so as to remove the upper portion thereof laterally away from the lower end of the wall 16 after which the supplemental core may be readily withdrawn out of the neck of the bag as shown in full lines in Fig. 6. 30 It is thus apparent that I have provided a novel type of seamless liquid bag, for use as a water bag, fountain syringe bag or any of the other uses thereof provided with a seamless integral molded vertically central wall 16 for 35 the double function of keeping the bag in correct flat position in use and preventing the liquid therein from bowing it out of shape and spacing the side walls 18 thereof when not in use, a novel type of core for use in the molding thereof, a novel type of means for securing said core to said mold and an improved method of making such an improved molded liquid bag. 40 I employ the words "vertically"; "horizontally", etc., as applied to the bag in a vertical position in use regardless of its position on the mold. 45 It is understood that my invention is not limited to the specific embodiments shown or methods described and that various deviations may be made therefrom without departing from the spirit and scope of the appended claims. 50 What I claim is: 55 1. A core for use in making molded liquid bags, comprising a main core portion of the desired shape of the interior of said bag having a cut-out portion extending from above the center to the lower end thereof slightly offset from the vertical center thereof and a hole projecting upwardly through the neck thereof, a 60 supplemental core portion complementary to said cut-out portion except for a narrow vertical wall forming slit on the upper portion of the center side thereof extending vertically for a substantial distance each side of the center of said combined core portions and a rod projecting upwardly therefrom adapted to project through said hole in said main core portion and means to detachably clamp the end of said rod to said main core portion to rigidly 65 secure said core portions together in molding position whereby said first core portion may be withdrawn vertically upwardly from said molded bag through the distended neck thereof, and said supplemental core portion may be tilted laterally from said molded center wall and withdrawn upwardly through said neck. 70 2. A core for use in making molded liquid bags, comprising a main core portion of the desired shape of the interior of said bag having a cut-out portion extending from above the center to the lower end thereof slightly offset from the vertical center thereof, a supplemental core portion complementary to said cut-out portion except for a narrow vertical wall forming slit on the upper portion of the center side thereof extend- 75

- ing vertically for a substantial distance each side of the center of said combined core portions, means on said core portions to retain them in alignment and means to rigidly secure said core portions together in molding position whereby said first core portion may be withdrawn vertically upwardly from said molded bag through the distended neck thereof, and said supplemental core portion may be tilted laterally from said molded center wall and withdrawn upwardly through said neck.
6. A core for use in making molded liquid bags, comprising a main core portion of the desired shape of the interior of said bag having a cut-out portion extending from above the center of the lower end thereof and a hole projecting upwardly through the neck thereof, a supplemental core portion complementary to said cut-out portion except for a narrow vertical wall forming slit extending vertically for a substantial distance each side of the center of said combined core portions and a rod projecting upwardly therefrom adapted to project through said hole in said main core portion, means on said core portions to retain them in alignment and means to detachably clamp the end of said rod to said main core portion to rigidly secure said core portions together in molding position whereby said first core portion may be withdrawn vertically upwardly from said molded bag through the distended neck thereof, and said supplemental core portion may be tilted laterally from said molded center wall and withdrawn upwardly through said neck.
7. A core for use in making molded liquid bags, comprising a main core portion of the desired shape of the interior of said bag having a cut-out portion extending from above the center to the lower end thereof, a supplemental core portion complementary to said cut-out portion except for vertical wall forming slit means extending vertically for a substantial distance each side of the center of said combined core portions and means to rigidly secure said core portions together in molding position whereby said first core portion may be withdrawn vertically upwardly from said molded bag through the distended neck thereof, and said supplemental core portion may be tilted laterally from said molded center wall and withdrawn upwardly through said neck.
8. In a liquid bag molding apparatus, a lower mold having a hemi-liquid bag and neck concavity and a flat concavity extending from above said neck concavity to the end wall of said mold having holes within, core means adapted to receive a cover of rubber or other plasticizable material to be vulcanized and/or molded and to lie therewith in a molding position in said lower mold, including a main core portion of the desired shape of the interior of the bag and of the thickness of the bag except for the rounded edges and constricted neck thereof and a flat portion of the thickness of said bag above the neck thereof adapted to lie in said flat concavity in said mold, having holes therein aligned with said mold holes, and having a cut-out portion slightly offset from the vertical central line thereof including a base portion, a center portion of less width, said base portion having holes projecting upwardly therefrom in said core and said center portion having vertical grooves extending laterally inwardly thereof, and an upper portion of less width extending laterally on one side of the vertical central line thereof a slight distance and a substantial distance on the other side thereof, said main core also having a hole extending vertically upwardly from said second offset side of said upper cut-out portion to the top portion of said core, a supplemental core portion substantially complementary to the cut-out portion, having a complementary base having pins projecting vertically upwardly therefrom within said main core holes, a center portion having splines projecting laterally thereof within said main core grooves, and an upper portion of less width than said cut-out upper portion, extending from the second side of said cut-out to a line spaced from the vertical central line of said core an amount equal to the amount that the first side of said cut-out is spaced from said vertical center, to form a liquid bag wall forming slit extending vertically near the center of said composite core, and a rod projecting from the upper portion thereof through said hole in said main core and having a threaded end extending beyond the mold end wall, a nut threaded on said rod end to clamp said mold portions together, means extending through said aligned holes in said main core flat portion and lower mold to securely retain said core to said lower mold and an upper mold having a cooperating hemi-liquid bag and neck and flat concavity to overlie said core and rubber covering thereof to mold the exterior of said liquid bag with said lower mold.
9. Core means adapted to receive a cover of rubber or other plasticizable material to be vulcanized and/or molded and to lie therewith in a molding position in a mold, including a main core portion of the desired shape of the interior of the bag and of the thickness of the bag except for the rounded edges and constricted neck thereof having a cut-out portion slightly offset from the vertical central line thereof including a base portion, a center portion of less width, and an upper portion of less width extending laterally on one side of the vertical central line thereof a slight distance and a substantial distance on the other side thereof, a supplemental core portion substantially complementary to the cut-out portion, having a complementary base, a center portion and an upper portion of less width than said cut-out upper portion, extending from the second side of said cut-out to a line spaced from the vertical central line of said core an amount equal to the amount that the first side of said cut-out is spaced from said vertical center, to form a liquid bag wall forming slit extending vertically near the center of said composite core, and means to detachable secure said core portions together.
10. Core means adapted to receive a cover of rubber or other plasticizable material to be vulcanized and/or molded and to lie therewith in a molding position in a mold, including a main core portion of the desired shape of the interior of the bag and of the thickness of the bag except for the rounded edges and constricted neck thereof having a cut-out portion slightly offset from the vertical central line thereof including a base portion, a center portion of less width, and an upper portion of less width extending laterally on one side of the vertical central line thereof a slight distance and a substantial distance on the other side thereof, a supplemental core portion substantially complementary to the cut-out portion, having a complementary base, a center portion and an upper portion of less width than said cut-out upper portion, extending from the second side of said cut-out to a line spaced from the vertical central line of said core an amount equal to the amount that the first side of said cut-out is spaced from said vertical center, to form a liquid bag wall forming slit extending vertically near the center of said composite core, and means to detachable secure said core portions together.

portion of less width than said cut-out upper portion, extending from the second side of said cut-out to a line spaced from the vertical central line of said core an amount equal to the amount that the first side of said cut-out is spaced from said vertical center, to form a liquid bag wall forming slit extending vertically near the center of said composite core.

11. Core means adapted to receive a cover of rubber or other plasticizable material to be vulcanized and/or molded and to lie therewith in a molding position in a mold, including a main core portion of the desired shape of the interior of the bag and of the thickness of the bag except for the rounded edges and constricted neck thereof and a flat portion of the thickness of said bag above the neck thereof adapted to lie in said flat concavity in said mold, having holes therein and having a cut-out portion slightly offset from the vertical central line thereof including a base portion, a center portion of less width, said base portion having holes projecting upwardly therefrom in said core and said center portion having vertical grooves extending laterally inwardly thereof, and an upper portion of less width extending laterally on one side of the vertical central line thereof a slight distance and a substantial distance on the other side thereof, said main core also having a hole extending vertically upwardly from said second offset side of said upper cut-out portion to the top portion of said core, a supplemental core portion substantially complementary to the cut-out portion, having a complementary base having pins projecting vertically upwardly therefrom within said main core holes, a center portion having splines projecting laterally thereof within said main core grooves, and an upper portion of less width than said cut-out upper portion, extending from the second side of said cut-out to a line spaced from the vertical central line of said core an amount equal to the amount that the first side of said cut-out is spaced from said vertical center, to form a liquid bag wall forming slit extending vertically near the center of said composite core, and a rod projecting from the upper portion thereof through said hole in said main core and having a threaded end extending beyond the mold and the wall, and a nut adapted to be threaded on said rod end to clamp said core portions together.

12. In a liquid bag molding apparatus, a lower mold having a hemi-liquid bag and neck concavity, core means adapted to receive a cover of rubber or other plasticizable material to be vulcanized and/or molded and to lie therewith in a molding position in said lower mold, including a main core portion of the desired shape of the interior of the bag and of the thickness of the bag except for the rounded edges and constricted neck thereof having a cut-out portion slightly offset from the vertical central line thereof including a base portion, a center portion of less width, and an upper portion of less width extending laterally on one side of the vertical central line thereof a slight distance and a substantial distance on the other side

thereof, a supplemental core portion substantially complementary to the cut-out portion, having a complementary base, a center portion and an upper portion of less width than said cut-out upper portion, extending from the second side of said cut-out to a line spaced from the vertical central line of said core an amount equal to the amount that the first side of said cut-out is spaced from said vertical center, to form a liquid bag wall forming slit extending vertically near the center of said composite core, and an upper mold having a cooperating hemi-liquid bag and neck concavity to overlie said core and rubber covering thereof to mold the exterior of said liquid bag with said lower mold, means to detachably secure said core portions together and means to retain said core in position within said mold.

13. In a liquid bag molding apparatus, a lower mold having a hemi-liquid bag and neck concavity, core means adapted to receive a cover of rubber or other plasticizable material to be vulcanized and/or molded and to lie therewith in a molding position in said lower mold, including a main core portion of the desired shape of the interior of the bag and of the thickness of the bag except for the rounded edges and constricted neck thereof having a cut-out portion slightly offset from the vertical central line thereof including a base portion, a center portion of less width, said base portion having holes projecting upwardly therefrom in said core and said center portion having vertical grooves extending laterally inwardly thereof, and an upper portion of less width extending laterally on one side of the vertical central line thereof a slight distance and a substantial distance on the other side thereof, said main core also having a hole extending vertically upwardly from said second offset side of said upper cut-out portion to the top portion of said core, a supplemental core portion substantially complementary to the cut-out portion, having a complementary base having pins projecting vertically upwardly therefrom within said main core holes, a center portion having splines projecting laterally thereof within said main core grooves, and an upper portion of less width than said cut-out upper portion, extending from the second side of said cut-out portion to a line spaced from the vertical central line of said core an amount equal to the amount that the first side of said cut-out is spaced from said vertical center, to form a liquid bag wall forming slit extending vertically near the center of said composite core, and a rod projecting from the upper portion thereof through said hole in said main core and having a threaded end extending beyond the mold and the wall, a nut threaded on said rod end to clamp said mold portions together and an upper mold having a cooperating hemi-liquid bag and neck to overlie said core and rubber covering thereof to mold the exterior of said liquid bag with said lower mold.

ANTONIO RICHARDS.
